UNITED STATES PATENT OFFICE.

JAMES B. CASSADY, OF BALTIMORE, MARYLAND, ASSIGNOR TO THE PERFECT BOTTLE CAP COMPANY, OF BALTIMORE, MARYLAND, A CORPORATION OF DELAWARE.

BOTTLE-SEALING MACHINE.

1,161,924.

Specification of Letters Patent. Patented Nov. 30, 1915.

Application filed June 14, 1911. Serial No. 633,083.

To all whom it may concern:

Be it known that I, JAMES B. CASSADY, a citizen of the United States, residing in the city of Baltimore, in the State of Maryland, have invented certain new and useful Improvements in Bottle-Sealing Machines, of which the following is a full, clear, and exact specification.

My invention relates to machines for sealing bottles with metallic caps, of the type applicable when the bottle has an annular head adapted to be covered by a metallic cap having a crown portion with depending annular flange adapted to be bent, crimped or compressed against the annular head of the bottle below the lip thereof.

Such machines have long been known in the art and comprise, speaking generally, a standard wherein is mounted a bottle support beneath and in vertical alinement with an overhanging vertically-reciprocating capping head guided from a bracket on the standard, motion being imparted to the capping head and to a cap-feeding device, comprising a chute leading to a slot in the capping head, which latter is, as shown in the drawings, a hollow body of two internal diameters, a shoulder near the base, and a coiled spring within the interior.

My invention consists, in a sealing mechanism adapted to be removably applied to and supported in the capping head of such machine; and has for its object to simplify the construction and operation thereof, and to cause its elements to co-act automatically and with absolute certainty, to compress and crimp the cap flange on the bottle head solely by the pressure exerted by the contacting thrust of the latter, against a movable member of my sealing head, and to release the capped bottle solely by a thrust of said sealing element in the opposite direction, which restores the parts to normal position.

Mechanism embodying the principles of and exemplifying my invention is illustrated in the embodiment thereof shown in the accompanying drawings, wherein:

Figure 1 is a sectional elevation of a complete bottle-sealing machine. Fig. 1^a is a sectional view of the bottle-supporting member. Fig. 2 is an enlarged elevation of

the external casing member of my new sealing head. Figs. 3 and 4 are sections taken on the line 3—3 of Fig. 2 showing the two 55 positions respectively of the sectional gripping member, relatively to the cam-acting casing member, and to the bottle head and cap to be sealed thereon. Fig. 5 is a section through both members of the sealing head, 60 on line 5—5 of Fig. 3, and Fig. 6 is a bottom plan view of the sealing head with the sectional gripping member in the position shown in Fig. 4.

Referring now to said drawings, I will 65 first describe the portions of the capping machine, shown in Fig. 1, including the novel features which I have embodied in the bottle-support shown in section in Fig. 1^a.

The frame or standard comprises a base 1 70 from which rises a column 2 wherein is mounted a plunger-rod 3 actuated through suitable geared shafting driven by a pulley 4, controlled by a clutch, and operated by a treadle 5. The plunger rod 3 projects beyond the upper end of the column 2, and rigid with its upper end is a laterally-extending bracket 16 from which rises a standard 17 carrying a hopper 18 containing the bottle caps and mechanism of a known type, 80 indicated at 19, 20, 21, 22, 23 and 24, for feeding the caps into a chute indicated in dotted lines on Fig. 1, down which they pass singly to a receiving slot near the mouth of the capping head 25 with which the end of 85 the chute communicates. A bracket 15, on the column 2 co-operates with said cap-feeding mechanism to support a rod 22 and a spring 23 coiled around it between said bracket and the hopper actuating devices 90 aforesaid, said spring aiding in restoring said devices alternately to normal upward position.

It will be readily understood that the hopper follows the vertical reciprocating movement of the plunger rod 3 and as the rod 22 is fixed to the bracket 15, in the operation of the machine the spring 23 is compressed and as above stated aids in restoring the hopper and feeding devices to normal upward position.

The capping-head element 25 is a hollow cylindrical body with a flaring mouth, and it is mounted rigidly on the aforesaid

bracket 16, so that it and the hopper have a vertically-reciprocating motion imparted to them simultaneously by the plunger rod 3. The capping head is engaged by the 5 guide 15 to maintain its reciprocation in a true vertical plane. The capping head is bored in two diameters to provide a shoulder 29 and is adapted to receive within its larger interior bore, below the shoulder 29, 10 a sealing head, indicated at 26 in Fig. 1; said head 26 resting normally upon a shoulder 27 near the mouth of and within the capping head 25, and a coiled spring 28 within the smaller interior bore of the capping head 25 serves primarily to hold the sealing head 26 yieldingly in place on said shoulder, and secondarily to cushion it on an upward movement which is definitely limited by the upper shoulder 29 in the capping head. 20

The bottle-supporting device must necessarily align with the capping mechanism; it must to some extent yield vertically to pressure on the bottle head in sealing, and must 25 be adjustable vertically to accord with the varying heights of bottles to be capped. To these ends I construct it in the following novel manner: Referring to Fig. 1, will be seen an arm 6 projecting laterally from the 30 column 2 and in this arm is threaded a hollow sleeve or casing 7, see section Fig. 1^a, which carries on its upper end a suitably cupped bottle-supporting plate 8, the aforesaid threaded connection between the casing 35 7 and arm 6 permitting the former to be adjusted vertically in the latter to suit the height of the bottle to be capped. The plate 8 is provided with a central and depending supporting rod 9 having an annular enlargement 10 near its lower end, which latter enters a coiled spring 11 housed within the casing 7; the enlargement 10 resting upon the spring; and a screw plug 12 inserted in the lower end of the casing serves to 40 close the same and support the spring. The casing is bored to provide a shoulder 13 which definitely limits the upward movement of the plate-supporting rod 9, while on a downward movement thereof the spring 45 11 will yield under the pressure applied to the bottle head by the capping mechanism. 50

I will now describe, by reference to Figs. 2 to 6 inclusive, the more important feature of my invention. This consists of the 55 sealing head 26 shown in section in its two operative positions, in one of which its elements are engaged in compressing the crown and the annular flange of the cap on the lip and head of the bottle, and in the other position releasing the sealed bottle after the closure is effected. The sealing head consists of a hollow containing casing 26, preferably cylindrical, as shown, and necessarily so, if the interior of the capping head 25 of

the machine is of that shape; its peripheral wall is slotted at 32 to permit the play therein of a screw pin 31, acting as a stoppin to limit the reciprocatory movements of a carrier body 30 slidingly mounted within said casing 26; the lower and open end of said casing is bored to provide a conical peripheral wall 44, the perpendicular length of the cone being proportioned to accord with the length of the sectional gripping member hereinafter described, and the angularity of the conical surface being such that it will operate as a progressively-acting cam to contact with the lower half of each of a freely-rocking set of dependingly-supported sealing fingers 35, constituting a sectional gripping member, on a bottle-thrust movement which will cause said gripping member to recede within the cam-acting containing case, as illustrated in Fig. 4, and close around the bottle-head and the flange 85 of the cap thereon; while the same angularity of the conical cam surface aforesaid necessary to contact with and rock the sealing fingers to effect the sealing function, is equally sufficient, on a return thrust, to allow 90 a rocking movement of the sealing fingers in the opposite direction, to release the sealed bottle, restore the gripping member and its containing casing to initial normal and relatively inoperative position, as shown in Fig. 95 3, ready for a repetition of the first operation and function stated.

The sectional gripping member consists of an annularly-arranged series of sealing fingers 35, held assembled by an annulus 41, 100 which is preferably resilient, such as a spiral spring held in notch 42; they are so shaped at the top to hang dependingly and curved at the lower half, preferably, to best effect a cam-acting contact and also a suitable hugging 105 action against the bottle head. The lower portions of the fingers are formed with curved enlargements 43 which are adapted to ride upon the inclined face 44 of the head and be thereby compressed against the bottle 110 cap to crimp the same.

To suitably support the sectional gripping member with the containing cam-acting casing, and also effect a return movement of it to the aforesaid normal position 115 after it has performed its sealing function, I have provided a carrier comprising a body portion 30 fitted to slide within the bore of the casing 26, and having a central stem 37 which, if not integral with the body 30 is 120 held in position by a nut 38. This stem 37 is made with a basal enlargement 36 preferably guttered or grooved to form a ribbed ledge 34, which is most suitable and convenient to hang, dependingly by their hook-like upper ends, the sealing fingers 35 so that they will rock freely, in the direction of their length, but limited therein by contact 125

with the said enlarged end of the stem of the carrier.

A spring 33 is held within the top of the casing and bearing on the top of the carrier body, which obviously causes it to slide back into normal position (as in Fig. 3) on a release of the pressure of the thrust which, as shown in Fig. 4, has compressed such spring to put it under necessary tension.

10 The limit of such sliding movement of the carrier body, in both directions is, however, effected by a stop device, such as the screw-pin 31 extending into the periphery of the carrier body and playing in the slot 32 of the casing; and, to obtain the best results, the length of the carrier body 30 should be so proportioned relatively to the casing 26, that there will be sufficient space in the latter that the compression spring 33 and stop-
20 device comprising pin 31 and slot 32, may perform their described functions; and also that the lower horizontal plane of the carrier body 30, in normal position, will be coincident with the plane of the apex of the 25 cam-acting conical surface of the casing 26.

The principle of construction and mode of operation of the machine will be well understood from the description given; but it may properly be added that in the specific form 30 of the elements shown in the drawings, there are these advantages namely that the enlargement on the downwardly-extending stem of the carrier makes the first and yielding contact with the crown of the cap, 35 to effectually seat it on the lip of the bottle and to drive the annular flange of the cap down and around the bottle head, and this immediately before the sealing fingers begin their movement to close in against said 40 flange; and moreover said movement is not a sudden, but a progressive rocking movement due to the conical cam-surface which effects it.

The whole action of every element of my 45 new sealing head described is purely automatic, and not only is the pressure of the bottle head the sole means of causing such automatic action of the elements, but the force with which the sealing is effected is 50 exactly proportioned to the force of the thrust of the bottle. In addition to the yieldable mounting of the several parts of the capping mechanism, the like resiliency in an opposite direction of the bottle support (see Fig. 1^a) due to its novel construction as hereinbefore described, practically eliminates all tendency to crush and break the bottle in the act of sealing a cap thereon.

Having thus fully described my invention 55 what I claim as new and desire to secure by Letters Patent of the United States is:—

1. In a bottle sealing machine having a vertically reciprocating hollow capping head, a sealing head adapted to be operatively

supported therein, said sealing head comprising a spring-tensioning member slidable therein, including a stop device, an annular arranged series of curvilinear sealing fingers dependently supported, and a resilient encircling annulus to cause said fingers to rock longitudinally on their support as a pivot, said sealing head having an interior conical cam surface adapted to engage the lower curved ends of said fingers to rock them in one direction, and resilient means, acting on 75 said slidable member, to thereby rock said sealing fingers in the opposite direction.

2. In a bottle sealing machine having a vertically reciprocating capping head adapted to receive caps singly from a chute and deliver them to a sealing mechanism, of a sealing head operatively and removably mounted in said capping head; and comprising a containing casing having a conically bored terminal adapted to operate as 80 a progressively-acting cam, a crimping member comprising a plurality of independently mounted sealing fingers adapted to be rocked longitudinally in an inward direction, to seal a bottle cap, by a sliding contact with 90 said cam surface, a supporting device for said fingers slidably mounted in said casing; and means, including a spring and a stop device operating to impart a limited return thrust to said supporting device to 95 thereby rock the fingers in the opposite direction to restore them to normal and bottle-releasing position.

3. In a bottle-sealing machine, the combination with a hollow capping body, of a 100 hollow sealing head slidably supported within said body, and having a conically-bored lower end adapted to operate as a cam surface, a carrier slidably housed within the sealing head and provided with a depending annular ledge supported on a connecting stem, and an annularly arranged series of sealing fingers provided with hook-like upper ends fitting over said ledge to dependingly support the fingers thereon and 110 permit a longitudinal rocking movement thereof, the fingers having curved outer surfaces on their lower ends adapted to be engaged by the conical cam surface of the sealing head on an upward thrust of the carrier. 115

4. In a bottle sealing machine having a vertically reciprocating member, a hollow cylindrical sealing head, slidably supported in said member and having a slot in its peripheral wall and an interiorly conically-shaped cam surface, a carrier slidably mounted in said head, a stop device on the carrier playing in the slot in the head, a spring adapted to be tensioned by a sliding movement of the carrier within the head, 120 and a series of curved sealing fingers dependingly supported from their upper ends on the carrier and adapted to be rocked lon- 125

gitudinally in one direction by a sliding contact of their lower curved ends with the conical cam surface of the sealing head, and in the opposite direction solely by the spring-
actuated thrust of said carrier in the opposite direction.

In testimony whereof I have signed my

name to this specification in the presence of two subscribing witnesses.

JAMES B. CASSADY.
